UNITED STATES PATENT OFFICE.

HERBERT M. STURGIS, OF KANSAS CITY, MISSOURI, ASSIGNOR OF FIFTY-FIVE ONE-HUNDREDTHS TO F. E. WEAR, OF KANSAS CITY, MISSOURI.

MOP-HOLDER.

1,030,939.

Specification of Letters Patent.

Patented July 2, 1912.

Application filed October 30, 1911. Serial No. 657,641.

To all whom it may concern:

Be it known that I, HERBERT M. STURGIS, a citizen of the United States, residing at Kansas City, in the county of Jackson and State of Missouri, have invented certain new and useful Improvements in Mop-Holders, of which the following is a specification.

This invention relates to mop holders, and my object is to produce a device of this 10 character of simple, strong, durable and cheap construction.

To this end the invention consists in certain novel and peculiar features of construction and organization as hereinafter described and claimed; and in order that it 15 may be fully understood reference is to be had to the accompanying drawing, in which—

Figure 1, is an elevation of a fragment of 20 a mop holder embodying my invention. Fig. 2, is a section on the line II—II of Fig. 1. Fig. 3, is a section on the line III—III of Fig. 1. Fig. 4, is a section on the line IV—IV of Fig. 2. Fig. 5, is a perspective 25 view of a fragment of the mop handle. Fig. 6, is a perspective view of a ferrule forming a part of the mop holder. Fig. 7, is a perspective view of the mop cord or cloth clamp.

In the said drawings 1 indicates a handle 30 of the customary type used for mops and bifurcated at its head end to provide a pair of opposite jaws 2.

3 is a tapered ferrule adapted for use on the bifurcated end of the handle to bend 35 said jaws until they are clamped tightly together at the front end of the bifurcation.

4 is a clamp preferably made from wire of heavy gage, the same being bent to substantially U-form and then bent inwardly 40 in the reverse direction as at 5 so as to produce an eye 6, and substantially parallel legs 7, the diameter of the eye exceeding the distance between the legs. This clamp is adapted to be slipped into the ferrule at the 45 small or front end of the same, and to facilitate such insertion of the clamp into the ferrule the free ends of the legs 7 are bent to form the inwardly converging arms 8.

In practice the bunch of mop cord or the 50 mop cloth not shown, is slipped through the eye of the clamp. The legs of the latter are then slipped into the ferrule and the large end of the latter is fitted over the front end of the handle, the arms 2 of the same being 55 pressed inward slightly if necessary, though

in practice, the enlarged end of the ferrule may be slightly greater in diameter than the diameter of the front end of the handle. With the parts thus arranged heavy pressure is applied by any suitable means, not shown 60 to force the ferrule and clamp upon the handle, the clamp being so disposed that its legs within the ferrule shall fit in the bifurcation of the handle.

The operation of forcing the ferrule and 65 the clamp upon the handle and within the bifurcation thereof respectively, and the forcing of the jaws of the handle inward to clamp the clamp firmly in position is simultaneous, and in such operation the legs of 70 the clamp become embedded in the jaws of the handle, as will be readily understood by reference particularly to Figs. 2, 3, and 4. By reference to said figures it will be seen that the clamp is held reliably in position not only through the frictional contact 75 of the jaws with the legs of the clamp but also because said jaws come together between the legs and forward of the arms 8 thereof. It will also be understood by reference to Fig. 3 particularly, that the ferrule under the resistance offered by the jaws will assume an elliptic form in cross section at all points forward of its rear end, at which point it will retain its circular form, assuming 80 said elliptic form because the jaws of the clamp spring together and by thus springing together close the outer ends of the bifurcation so that it will be impossible for the clamp to be pulled out of the ferrule without causing arms 8 to tear through a substantially solid portion of the handle. It will also be apparent that because the eye of 85 the clamp is of such diameter that it swells outward beyond the ferrule, it is impossible 90 for the latter to be dislocated. The clamp locks the ferrule in position by preventing forward movement of the same and the ferrule locks the clamp in position by preventing separable movement of the jaws or outward movement of the legs of the clamp. 100

As it is obviously impossible for the clamp and ferrule to become detached from each other or from the handle, it is clear that the bunch of mop cord or mop cloth may be 105 clamped so tightly by the eye of the clamp against the end of the handle and ferrule, that it will be impossible for it to work loose and become detached in use.

From the above description it will be ap- 110

parent that I have produced a mop holder possessing the features of advantage enumerated as desired, and I wish it to be understood that while I have illustrated and 5 described the preferred embodiment of the invention I do not desire to be restricted to the exact details of construction shown and described, as obvious modifications will suggest themselves to one skilled in the art.

10 I claim:

1. In a mop holder, a handle bifurcated to form a pair of jaws at one end, a ferrule fitting upon the bifurcated end of the handle and holding said jaws in a forwardly 15 converging relation, and a clamp of substantially U-form, consisting of an eye forward of the ferrule and handle and legs fitting in the ferrule at diametrically opposite points and clamped between and embedded 20 in the inner faces of the said jaws.

2. In a mop holder, a handle bifurcated to form a pair of jaws at one end, a ferrule fitting upon the bifurcated end of the handle and holding said jaws in a forwardly converging relation, and a clamp of substantially 25 U-form consisting of an eye forward of the ferrule and handle and legs fitting in the ferrule at diametrically opposite points and clamped between and embedded in the inner faces of the said jaws; the eye of the 30 clamp being wider than and bearing against the front end of the ferrule to prevent forward movement thereof.

3. In a mop holder, a handle bifurcated 35 to form a pair of jaws at one end, a ferrule fitting upon the bifurcated end of the handle and holding said jaws in a forwardly converging relation, and a clamp of substantially 40 U-form consisting of an eye forward of the ferrule and handle and legs fitting in the ferrule at diametrically opposite

points and clamped between and embedded in the inner faces of the jaws; the free ends of the legs of the clamp terminating in in-turned arms.

4. In a mop holder, a handle bifurcated to form a pair of jaws at one end, a ferrule fitting upon the bifurcated end of the handle and holding said jaws in a forwardly converging relation, and a clamp of substantially 45 U-form consisting of an eye forward of the ferrule and handle and legs fitting in the ferrule at diametrically opposite points and clamped between and embedded in the inner faces of the jaws; the free ends 50 of the legs of the clamp terminating in in-turned arms, and the eye of the clamp being wider than and bearing against the front end of the ferrule to prevent forward movement thereof.

5. A mop holder comprising a handle, bifurcated to provide a pair of opposite jaws at one end, a ferrule fitting upon the bifurcated end of the handle and tapering forwardly and holding the jaws in a forwardly converging relation with the front extremities of their inner faces in contact, a U-shaped wire clamp with its legs fitting between the jaws of the handle and against the ferrule at diametrically opposite sides 65 of the same, the closed end or eye of the clamp being of greater width than and bearing against the front end of the ferrule and the free ends of the legs of the clamp terminating in inwardly projecting arms.

70 In testimony whereof I affix my signature, in the presence of two witnesses.

HERBERT M. STURGIS.
